US00D775603S

(12) **United States Design Patent** (10) **Patent No.:** **US D775,603 S**
(45) **Date of Patent:** **** Jan. 3, 2017**

(54) **PORTION OF A JUKEBOX**

(71) Applicant: **TouchTunes Music Corporation**, New York, NY (US)

(72) Inventors: **Michael Tooker**, Pointe-Claire (CA); **Charles Garneau**, Bois-des-Filion (CA); **Ed Rivera**, New York, NY (US); **Eric Saint-Jacques**, Town of Mount Royal (CA); **Benoit Tessier**, Boisbriand (CA); **Jean Gauthier**, Sainte-Thérèse (CA)

(73) Assignee: **TouchTunes Music Corporation**, New York, NY (US)

(**) Term: **15 Years**

(21) Appl. No.: **29/531,252**

(22) Filed: **Jun. 24, 2015**

Related U.S. Application Data

(63) Continuation of application No. 29/477,654, filed on Dec. 24, 2013, now Pat. No. Des. 734,735.

(51) **LOC (10) Cl.** **14-01**

(57) **CLAIM**

The ornamental design for a portion of a jukebox, as shown and described.

DESCRIPTION

FIG. 1 is a front perspective view of a jukebox showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side view thereof; and,

FIG. 7 is a left side view thereof.

The broken lines represent environmental structure and form no part of the claimed design. The dotted lines represent the boundary between claimed and unclaimed subject matter and form no part of the claimed design.

1 Claim, 5 Drawing Sheets
